VALVE OPERATING MECHANISM

Charles S. Burnett, San Francisco, Calif.

Application July 19, 1933, Serial No. 681,139

7 Claims. (Cl. 123—90)

(Granted under the act of March 3, 1883, as
amended April 30, 1928; 370 O. G. 757)

This invention described herein may be manufactured and used by or for the Government for governmental purposes without the payment to me of any royalty thereon.

5 This invention relates to a valve operating mechanism for engines of the internal combustion type and more particularly it is directed to a governor control mechanism for regulating the time of the intake valves thereof.

10 One of the objects of my invention is to provide a governor control mechanism including an auxiliary shaft having a valve actuating cam mounted thereon for engines of the internal combustion type to vary the time of closing of the intake valves thereof in accordance with the speed of the driving mechanism of the engine without regard to the load carried by the driving mechanism.

Another object of my invention is to effect the 20 last mentioned object without increasing or decreasing the lift of the valve.

Another object is to provide a governor control mechanism which is adapted to vary the duration of the intake period of internal combustion engines as a function of the engine speed.

An important object is to make it possible and practicable, to delay the time of closing the intake valves of internal combustion engines using gas fuel for the purpose of increasing volumetric efficiency.

The governor control mechanism including the auxiliary shaft having an actuating cam mounted thereon is subject to being used in any device wherein intake and exhaust valves are employed 35 and to operate either the intake or exhaust valves whether their cams are mounted on separate shafts or on the same shaft but is primarily provided for operating the intake valves of internal combustion engines.

40 The present invention comprises generally a speed governor mounted on an auxiliary cam shaft including an actuating cam for the intake valves of internal combustion engines in such a manner that as the speed of the engine fluctuates it varies the timing of the auxiliary actuating cam to control the time of closing of the intake valves at high speeds thus improving the volumetric efficiency of the engine.

In order that my invention may be understood 50 reference is had to the accompanying drawings forming a part of the specification in which like parts are indicated by similar reference characters and in which:

Fig. 1 is a vertical sectional view partly in elevation of one form of engine embodying an aux-

iliary cam shaft of my invention for controlling the time of closing the intake valve of the engine;

Fig. 2 is a front elevation of a gear drive used in carrying out my invention including my improved valve operating mechanism mounted on 60 the auxiliary cam shaft;

Fig. 3 is a side elevation thereof;

Fig. 4 is an enlarged longitudinal cross sectional view thereof taken on line 4—4 of Fig. 2;

Fig. 5 is an enlarged vertical sectional view of 65 the governor control mechanism taken on line 5—5 of Fig. 3;

Fig. 6 is an enlarged detail view in elevation of a post member used in the control mechanism;

Fig. 7 is a perspective detail view thereof illustrating the manner in which the post member is 70 operated; and

Fig. 8 is a side elevation partly in section of a modified form of post member secured to a member of my improved control mechanism. 75

In the illustrated embodiment characterizing my invention A indicates generally an engine of the internal combustion type which in the present illustration is shown as provided with a cylinder (1) and separate cam shafts (2) and (3) 80 having actuating cams (4) and (5) mounted thereon for operating the intake and exhaust valves (6) and (7) respectively. It is to be understood however, that I do not limit myself either as to the number of cylinders or the type of 85 engine and further to whether the intake and exhaust valves of the engine are mounted on separate cam shafts or on the same shaft in which my invention may be employed, said invention being well adapted for engines of substantially any type, as well as the poppet valve type, at present illustrated by making suitable modifications and changes in location of elements as will be understood by those skilled in the art.

The cylinder (1) is provided with a piston (8) 95 pivotally connected by the pitman (9) to the crank shaft (10) which is secured to the power shaft (11). The push rod (12) of the intake valve 6 of the engine is made in sections to provide an upper and lower portion (13) and (14) 100 respectively which are joined together at one end by means of a substantial C-shaped member (15) which is provided for bridging the push rod (12) around the auxiliary shaft (17) of my improved valve actuating mechanism. The free end of the lower portion (14) of the push rod (12) is provided with a follower head (16) which is adapted to ride on the actuating cam (4) provided on the regular intake cam-shaft (2).

The auxiliary shaft (17) is provided with an 110

Fig. 1 is a vertical sectional view partly in elevation of one form of engine embodying an aux-

actuating cam (18) which is designed to control the time of closing of the intake valve (6) by acting against the follower head (19) provided on the lower end of the upper portion (13) of 5 the push rod (12) and to hold the intake valve open after it has been released by the regular cam (4).

The cam-shafts (2), (3) and the auxiliary shaft (17) are driven by the power shaft (11) through 10 the intermediary of gears (20), (21), (22) and a ring gear (23) respectively. An intermediate non-metallic idler gear, if desired, may be provided between certain of said gears to cause a more silent operation thereof.

15 The auxiliary cam-shaft (17) carries an integral hub and flange member (24) which is fixably secured thereto by a key (25). The hub portion of the member (24) has the ring gear (23) rotatably mounted thereon and is made longer 20 than the width of the ring gear (23) to provide an extending portion (26) containing a screw threaded well (27) on diametrically opposite sides thereof for receiving a threaded stem (28) of posts (29), which are screw-threaded in the wells (27) and adapted to be moved vertically up 25 and down therein. In order to hold the ring gear (23) in proper position on the member (24) and to provide a guide for the posts (29), a collar (30) containing an aperture (31) on opposite sides thereof, in alignment with the wells (27) of the member (24) is mounted on the projecting portion (26) of the member (24).

The heads (32) of the posts (29) are provided 30 with gear teeth (33) which extend around a portion of the outer periphery thereof as shown in Fig. 6 of the drawings. The gear teeth (33) of the posts (29) are adapted to mesh with rack teeth (34) provided on the upper and lower portion of the ring gear (23) and are so formed 35 and arranged in spaced relation to each other as to properly engage the rack teeth (34) of the ring gear when the posts (29) are rotated and moved longitudinally in the wells (27). A cap (35) provided with an outwardly projecting portion (36) is mounted on each of said posts (29). The projecting portion (36) of the posts (29) 40 are connected to links (37) by any suitable means such as by a ball and socket member (38). The links (37) are in turn connected to arms (39) of a governor (40) in any suitable manner such 45 as by a ball and socket member (41). One end of the arms (39) of the governor (40) is pivotally connected to a clamp fixably secured to the auxiliary cam-shaft (17) while each of the free ends 50 of the arms (39) is provided with a governor ball (42) containing a locking member (43) in the form of a projecting tooth which is adapted to mesh with teeth (44) provided on the upper and lower portion near the periphery of the ring gear (23) for taking up the shock on the governor 55 arms (39) due to sudden stopping or starting of the engine or when the engine is suddenly accelerated or decelerated when running at low speeds. In order to retract the various parts of 60 the governor control mechanism to normal position after the force of the governal balls (42) have relaxed at low speeds or at rest, a helical spring (45) is connected between each of the arms (39) of the governor (40) and the member (24).

The modified form of post (29') illustrated in Figure 8 of the drawings, which may be used in carrying out my invention, is provided with a reduced end portion (46) and is rotatably mounted 75 on the collar (30') by means of a cap screw (47)

which screws into a tapped hole provided in the reduced end portion (46). The head (32') of the post (29') is provided with gear teeth (33') which extend in stepped formation around a portion of the outer periphery of the post. Each of the teeth (33') have a declining pitch with respect to the others for engaging the rack teeth (34) of the ring gear (23) at different points thereof when the post is rotated by the governor (40).

80 In operation, my device functions as follows: As the speed of the engine fluctuates the governor (40) pulls on the links (37) which in turn pull on the projecting portion (36) of the caps (35) provided on the posts (29) or (29') thereby rotating the posts. The gear teeth (33) of the posts meshing with the rack teeth (34) of the ring gear (23) causes the ring gear to be rotated in a counter-clockwise direction as shown by the arrow. This action causes the ring gear (23) to have a different position with relation to the auxiliary shaft (17) with the result that the cam mounted on the auxiliary shaft (17) is retarded with respect to the actuating cam mounted on the regular cam-shaft, thereby causing the actuating cam on the auxiliary shaft to effect a greater or lesser duration of the intake period than that which would be produced by the regular cam.

85 It will thus be seen that I have provided a highly novel, simple and efficient form of valve operating mechanism that is well adapted for all the purposes designated. Even though I have herein shown and described my device as comprising certain structural elements it is nevertheless to be understood that changes may be made therein without departing from the spirit or scope of my 90 invention, which broadly comprises the combination of a regular cam and cam-shaft for actuating a valve periodically, an auxiliary cam and cam-shaft, a hub and flange member fixably mounted on said auxiliary shaft, a screw-threaded well 95 provided on each side of said hub and flange member, an adjustable gear rotatably mounted on said hub and flange member, a collar mounted on said hub and flange member adjacent said adjustable gear, apertures provided in said collar in alignment with the said wells of said hub and flange member, said adjustable gear controlled by a ball governor mounted on said auxiliary cam and connected by a linkage which varies the timing of the auxiliary cam to retard it with an 100 increase of speed, said linkage comprising a post member mounted in each of said aligned apertures of said collar and wells of said hub and flange member, a cap provided with an outwardly projecting portion provided on each of said post members, spaced gear teeth provided on each of said post members adapted to mesh with rack teeth provided on said adjustable gear, links connecting said post members to said ball governor, one end of said links swivelly connected to the 105 projecting portion of the caps of said post members and the other end thereof swivelly connected to arms of said ball governor, spring means for returning said valve controlling device to normal 110 inoperative position connected between the said arms of the ball governor and said collar, and means on the balls of said governor and the said adjustable gear for detachably holding said ball governor in locked position, said locking means comprising a projecting tooth on the balls of said 115 governor and teeth on said adjustable gear.

120 Having described my invention what I claim as new and useful is:—

1. In a valve controlling device, the combination of a regular cam and cam-shaft for actuati- 125

- ing the valve periodically, an auxiliary cam and cam-shaft driven by the regular cam-shaft through an adjustable gear which is controlled by a speed governor mounted on the auxiliary shaft and connected by a linkage which varies the timing of the auxiliary cam to retard it with an increase in speed. 5. In a valve controlling device, the combination of a regular cam and cam-shaft for actuating the valve periodically, an auxiliary cam and cam-shaft driven by the regular cam-shaft through an adjustable gear which is controlled by a speed governor mounted on the auxiliary shaft and connected by a linkage which varies the timing of the auxiliary cam to retard it with an increase in speed, and means for returning said valve controlling device to normal inoperative position. 6. In a valve controlling device, the combination of a regular cam and cam-shaft for actuating the valve periodically, an auxiliary cam and cam-shaft driven by the regular cam-shaft through an adjustable gear which is controlled by a speed governor mounted on the auxiliary shaft and connected by a linkage which varies the timing of the auxiliary cam to retard it with an increase in speed, means for returning said valve controlling device to normal inoperative position, and means for detachably locking said speed governor to said adjustable gear. 7. In a valve controlling device, the combination of a regular cam and cam-shaft for actuating the valve periodically, an auxiliary cam and cam-shaft, a hub and flange member fixably mounted on said auxiliary cam-shaft, said auxiliary cam-shaft driven by said regular cam-shaft through an adjustable gear rotatably mounted on said hub and flange member and controlled by a speed governor fixably mounted on the auxiliary cam-shaft, said speed governor connected by a linkage which varies the timing of the auxiliary cam to retard it with an increase in speed, said linkage comprising post members rotatably mounted on said hub and flange member and provided with gear teeth for meshing with rack teeth provided on said adjustable gear and links connecting said speed governor to said post members. 8. In a valve controlling device, the combination of a regular cam and cam-shaft for actuating the valve periodically, an auxiliary cam and cam-shaft, a hub and flange member fixably mounted on said auxiliary cam-shaft, wells provided in said hub and flange member, an adjustable gear and collar mounted on said hub and flange member, screw threaded post members movably mounted on said collar and adapted to project into said wells, spaced gear teeth pro- vided on a portion of the periphery of said post members, a cap including a projecting portion on the upper end of each of said post members, said adjustable gear rotatably mounted on said hub and flange members and a speed governor mounted on said auxiliary cam-shaft for controlling said adjustable gear and connected by links to the said projecting portion of said post members, the said gear teeth of said post members meshing with rack teeth provided on said adjustable gear. 9. In a valve controlling device, the combination of a regular cam and cam-shaft for actuating the valve periodically, an auxiliary cam and cam-shaft, a hub and flange member fixably mounted on said auxiliary cam-shaft, said auxiliary cam-shaft driven by said regular cam-shaft through an adjustable gear provided with rack teeth and rotatably mounted on said hub and flange member and controlled by a speed governor fixably mounted on the auxiliary cam-shaft, a collar mounted on said hub and flange member adjacent said adjustable gear, linkage connecting said speed governor which varies the timing of the auxiliary cam to retard it with an increase in speed, said linkage comprising screw-threaded post members rotatably mounted on said collar, hub and flange member and provided with gear teeth for meshing with the rack teeth of said adjustable gear, links connecting said speed governor to said post members, means for returning said valve controlling device to normal inoperative position and means for detachably locking said speed governor to said adjustable gear. 10. In a valve controlling device, the combination of a regular cam and cam-shaft for actuating the valve periodically, an auxiliary cam and cam-shaft, a hub and flange member fixably mounted on said auxiliary cam-shaft, wells provided in said hub and flange member, a post member movably mounted in each of said wells, spaced gear teeth provided on a portion of the periphery of said post member, a cap including a projecting portion on the upper end of each of said post members, an adjustable gear rotatably mounted on said hub and flange member and controlled by a speed governor mounted on the auxiliary cam-shaft, said speed governor connected by links to the said projecting portion of the caps of said post members, and the said gear teeth of said post members meshing with rack teeth provided on said adjustable gear, means for returning said valve controlling device to normal inoperative position and means detachably locking said speed governor to said adjustable gear.
